MAIL-BAG-PICK-UP MECHANISM.

1,150,417.

Specification of Letters Patent. Patented Aug. 17, 1915.

Application filed April 27, 1914. Serial No. 884,611.

To all whom it may concern:

Be it known that I, GUY H. CHRISTY, a citizen of the United States, residing at Santa Cruz, in the county of Santa Cruz and 5 State of California, have invented new and useful Improvements in Mail-Bag-Pick-Up Mechanism, of which the following is a specification.

This invention relates to improvements in 10 mail bag pick-up mechanism of the type disclosed in my co-pending application filed March 16, 1914, Ser. No. 824,897.

It is one of the objects of the present invention to provide a mail bag handling apparatus 15 which is capable of discharging or casting off mail bags or parcels at railway stations without stopping or slowing up the railway mail car.

It is also an object of the present invention to provide a mail bag handling apparatus which combines a cast-off mechanism and a means for picking up parcels from a 20 stationary support at a station past which the train or mail car is traveling.

25 The invention consists of a crane turnably supported upon the side wall of a car, which crane is adapted to be locked in a perpendicular position relative thereto, having a latch or bolt member for carrying mail bags, 30 or other parcels, and which may be tripped by a coacting abutment member at a predetermined station; and further includes a pick-up device, coöperable with a stationary support, with a detachable hook, to 35 which may be attached the mail bags, or other parcels, to be picked up and transferred to the traveling railway car.

It also comprises details of construction 40 which will be more fully explained by reference to the accompanying drawings, in which—

Figure 1 is a side elevation of the apparatus with the parts in the pick up position. Fig. 2 is a vertical sectional view on line 45 $\alpha-\alpha$, Fig. 1, looking in the direction of the arrow. Fig. 3 is an end elevation of the mechanism carried by the car.

In the drawings, 2 represents a portion of a railway car having a doorway or window 50 3. There is secured on one side of the car suitable bearings 4, in which is supported a crane 5 turnable about a vertical axis in the bearings 4. The crane 5 is provided at its lower inner end with a pintle 6, through 55 which and the adjacent bearing may be run

a locking pin 7, connected by a cord or equivalent 8 to the crane 5; the pin being adapted to lock the crane in the desired angular position with relation to the side of the car.

60 The cast-off device comprises a triangular bow or loop 9, hinged on a bearing 10 of the crane, and has its upper end projecting somewhat, as at 11, so that, when the bow 9 is adjusted in the dotted line position shown in Fig. 2, it is locked therein by a lever or dog 12 secured on a crank-shaft 13 mounted on the crane 5. The outer end of the crank-shaft 13 is provided with a striking lever 14, which, when turned to the vertical dotted line position indicated in 65 Fig. 2, is adapted to abut a fixed striker 15, Fig. 1, arranged in its path. The rotation of the crank-shaft 13, when the striking arm 14 is stripped by the device 15, carries the 70 dog 12 from engagement with the end 11 of the bow 9 and this is thrown to the full line position, Fig. 2, by a contractile spring 16 connected thereto and to a convenient part 75 of the crane 5.

80 In its lowermost position the bow 9 moves into engagement with curved guide members 17 connected to a suitable tower or stationary support 18. In line with the curved guides 17 there is provided a hook 19 with 85 an upwardly extending arm having an eye 20 with a safety latch 21 which is adapted to close the mouth of the opening of the hook. The hook 19 is readily mounted upon and demountable from a pin or bearing member 90 22 of the standard 18; the hook 19 having an inclined slot 23 for the reception of the stationary pin 22. The hook 19 has a downwardly extending portion 24 to which may be suitably connected or attached the mail 95 bags or other parcels, indicated at 25, which are to be picked up from a station by the crane 5 of the railway car.

100 In operation, the station attendant attaches the mail bags or parcels 25 to the hook 19, which is adjusted with its slot 23 straddling the supporting pin 22 of the tower or standard 18, whereupon it will assume the position indicated in Fig. 2. As before stated, when the trip arm 14 of the 105 crank-shaft 13 is thrown in the direction indicated by the arrow, Fig. 2, the locking dog 12 releases the bow 9 so that it swings on its journal 10 to the lowermost position, and during its movement with the car will 110

be carried into engagement with the curved guides 17 over which it will slide, yieldably, and pass into the mouth of the hook 19, the upper end of which projects above the 5 top plane of the guides 17. After the lower end of the bow or pick-up device 9 has entered the hook 19, the safety pawl 21 falls outwardly again and thus locks the hook 19 onto the bow 9 so as to prevent the accidental separation of the parts until the 10 safety latch 21 is again turned in the eye 20 of the hook 19 to open the mouth of the hook and permit the removal of the hook from the bow.

15 The tower or post 18 is shown as turnably supported in a fixed base or bearing 18', and it may be locked in the desired angular position by suitable pins 18''. Thus the horizontally and upwardly projecting portions 20 of the tower 18 can be turned to a position to safely clear the mail receiving and delivering apparatus of the railway cars. In order to assist the operator or attendant in mounting a heavy parcel or bundle of bags 25 on the supporting pin 22 of the standard, I provide a suitable block and tackle 26, the hook of which may be connected to the mail hook 19. Upon the application of sufficient power to the tackle the parcel may be 30 easily lifted into position to allow the mounting of the hook 19 on the supporting pin 22.

When the apparatus is to be used for casting off or delivering mail bags or parcels at a station, the operator turns the 35 crank-shaft 13 to draw over a connecting link 27 mounted on the crank of the crank-shaft, the opposite end of the link being connected to a lever 28 of a rocker-shaft 29. The rocker-shaft 29 is provided with a lever 40 30, to the end of which is pivoted a pin or bolt 31 which is adapted to be turned into the horizontal position shown in dotted lines in Fig. 2 for insertion into a keeper 32 on the crane. There is mounted upon the bolt 45 31, when in a horizontal position and supported in the part 32, a bag or parcel to be delivered at a desired station. Upon the tripping of the striking lever 14 the crank-shaft 13 is revolved and the pick-up bail or bow is 50 withdrawn from the hanger 32 and thus drops the mail bags or other parcels when withdrawn from the keeper 32. Thus it will 55 be seen that I have provided a combined parcel delivering and receiving apparatus for moving vehicles, such as railway mail cars.

When the striking lever 14 is in an upright position, for engagement with the 60 striker, it is held in this position partly by the friction of the short end 11 of the bow 9 under tension of the spring 16 and also partly by the link 27 and its lever 28 to which latter is connected a tension spring 65 28'. This spring 28' is connected to a pend-

ant arm 5' of frame 5 and acts to yieldably thrust the bolt 31 into hanger 32, at the same time maintaining the lever 14 upright with the lug 12 imposed on the end 11. Upon the striking lever 14 engaging striker 70 15 the spring 28 yields and allows lever 14 to turn down, simultaneously withdrawing bolt 31, after which the spring contracts and throws the lever 14 and crank 13 to an indefinite position. 75

The bag delivering mechanism is the subject matter of my prior application filed March 16, 1914, Serial No. 824,897.

Having thus described my invention, what I claim and desire to secure by Letters Pat- 80 ent is—

1. In combination, a crane adapted to project from a car during the operation of transferring mails, a crank-shaft on the crane, a pick-up device mounted on the crane and normally retained inoperative by the crank-shaft, and parcel supporting means on the crane and operatively connected to the shaft for operation thereby to deliver an article, an operation of the crank-shaft releasing the pick-up device to an operative position and delivering the parcel. 90

2. In combination, a crane adapted to project from a car during the operation of transferring mails, a crank-shaft on the 95 crane, a pick-up device pivoted to the crane and releasably engaged by the crank-shaft for normally being retained inoperative and a parcel delivery means movably mounted on the crane and operable by the shaft to 100 effect a delivery, whereby on operating the crank-shaft the device is released to operative position and a deliverable movement imparted to the delivery means.

3. The combination in a mail bag cast-off and pick-up device, of a crane turnably connected to a railway car, a bolt upon which may be mounted the mail bags to be delivered and engageable with a keeper on the crane, a member normally held inoperative upon the crane and adapted to pick up a mail bag carrier at a station, and means for retracting the bolt to release the mail bags thereon for deposit at the station and permit of said member moving to an operative 115 position for co-operation with the mail bag carrier at the station. 105

4. In combination, a crane, a crank-shaft having a crank portion and a lever, a pick-up device pivoted between its ends to the 110 crane, the lever of the shaft being adapted to releasably engage one end portion of the device to hold the latter inoperative, a delivery means operatively connected to the crank portion of the shaft, and means for actuating the crank shaft to release the pick-up device to operative position and effect a delivery movement to the delivery means. 120

5. In a combined mail bag cast-off and pick-up device, a crane, a crank-shaft there- 125 130

on, a spring tensioned pick-up means pivoted on the crane for movement independent of the crank-shaft, a member on the crank-shaft to hold the pick-up means in retracted position, means to hold a parcel on the crane, means connected to the crank shaft to release the parcel, and means for actuating the crank-shaft to cause same to release the pick-up means and the parcel holding 10 means.

6. In a combined mail bag cast-off and pick-up device, a crane, a crank-shaft thereon, a spring tensioned pick-up means, a member on the crank-shaft adapted to engage with the pick-up means to hold the latter in inoperative retracted position, a keeper, a sliding pin coöoperating with the keeper to hold a parcel, means connecting the pin and crank shaft whereby the latter 15 upon movement will actuate the pin to re-

lease the keeper, and means for actuating the crank-shaft to cause same to release the parcel and pick-up means.

7. In combination with a crane, a crank shaft thereon, pick-up means mounted for movement on the crane independent of the crank-shaft, means connected to the crank-shaft for releasably holding the pick-up means inoperative, parcel holding means having a movable part operatively connected to the crank-shaft, and means to actuate the crank-shaft to release the parcel and the pick-up means. 25 30

In testimony whereof I have hereunto set my hand in the presence of two subscribing 35 witnesses.

GUY H. CHRISTY.
